Application September 18, 1948, Serial No. 49,883

10 Claims. (Cl. 200—12)

1

This invention relates to an electric switch, especially to a reversing switch for a direct current motor.

In the operation of direct current electric motors, it is likely to be dangerous to try to open the armature circuit with the armature still rotating. The reason for this is that the counter-electromotive force set up by the rotating armature is sufficient to cause substantial arcing across the switch terminals if an attempt is made to break the circuit.

It is an object of this invention to provide a reversing switch in which the armature circuit cannot be opened as long as the counterelectromotive force in the rotating armature is such as would cause destructive arcing if the circuit were opened. This and other objects are accomplished in a reversing switch in which the armature circuit is made and broken by the engagement and disengagement respectively of two sets of contacts, one set being reciprocable relative to the other. Relative reciprocation of the contacts is effected against a strong engaging spring by means of a cam and cam follower which supplies the necessary mechanical advantage to overcome the spring. The reciprocable set of contacts is mounted on a rod which passes through a coil, the coil being connected in the armature circuit. A magnet armature adjusted at one end of the coil is hingedly mounted for movement toward the coil to close an air gap, and a cam mechanism is connected to cause engagement of a stop with an abutment on the rod upon movement of the armature against the end of the coil. An indexing means is provided to assure alinement of the contacts for either forward or reverse operating position and to provide a third position in which one set of contacts lies between the other set of contacts. The indexing mechanism includes a serrated member mounted on the switch casing and an indexing finger mounted for reciprocation with the rod, and is so arranged that the reciprocable contacts may not be indexed when the contacts are engaged.

In the drawings:

Fig. 1 is a view in elevation of the indexing end of the switch showing the switch indexed so that the contacts of one set lie between the contacts of the other set. The cam mechanism is shown in the position in which the two sets of contacts lie substantially in the same plane.

Fig. 2 is a view in section substantially on line 2—2 of Fig. 1.

Fig. 3 is a view in elevation of the terminal end of the switch.

2

Fig. 4 is a view in section on line 4—4 of Fig. 2.

Fig. 5 is a view in section on line 5—5 of Fig. 2.

Fig. 6 is a view similar to Fig. 2 but showing the reciprocable contacts retracted out of the plane of the other contacts and axially displaced therefrom.

Fig. 7 is a view in section similar to Fig. 2 but showing the reciprocable contacts in engagement with their cooperating contacts. As shown in Fig. 7, indexing finger 78 occupies the notch 96 instead of the notch 94 as in Fig. 2.

Fig. 8 is a view in section on line 8—8 of Fig. 7.

Fig. 9 is a view in elevation of the indexing end of the switch showing the indexing finger in the position it occupies when the contacts occupy the relative position shown in Fig. 7.

Fig. 10 is a partial longitudinal section along the line 10—10 of Fig. 9.

Fig. 11 is a view similar to Fig. 9 but showing the indexing finger in the operating position which is the reverse of the operating position shown in Fig. 9.

Fig. 12 is a partial longitudinal section along the line 12—12 of Fig. 11.

Fig. 13 is an enlarged end elevation view similar to that shown in Fig. 1.

Fig. 14 is a partial side elevation view of the switch with the parts in the position shown in Fig. 13.

Fig. 15 is another end elevation view similar to Fig. 13 but showing the cam follower herein in the position it occupies when the reciprocable contacts are retracted out of engagement with their cooperating contacts.

Fig. 16 is a side elevation view showing the switch with the parts in the position shown in Fig. 15; and

Fig. 17 is a simple circuit diagram showing how one set of contacts is connected in the circuit of a D. C. motor.

A switch made according to this invention preferably includes a casing made up of an end member 2 having mounting ears 3, a side member 4, and a second end member 6. The end member 2 is made of a magnetic material and the end member 6 is made of a non-conducting material. The two end members and the side member are held together by a plurality of threaded members 8.

A first set of contacts 10, 12, 14 and 16 is yieldably mounted in the end member 6. As is best seen in Figs. 10 and 12, each of the first set of contacts consists of a cupshaped engaging member 18 which is preferably integral with a conductor rod 20 and is mounted in a recess 22 in the second end member 6. Between the end of

the cupshaped member 18 and the bottom of the recess, there is located a coil spring 24 which is adapted to bias the contact in good conducting engagement with the cooperating one of a second set of contacts to be described in detail below.

The outer end of each conductor rod is provided with a washer 26 and is threaded to receive a nut 28. A conductor strap 30 is clamped between washer 26 and nut 28 and electrically connects the conductor rod 20 with a terminal. The terminals are indicated generally at 32, 34, 36 and 38, for the cooperating contacts 10, 12, 14 and 16 respectively. Each of the terminals is securely anchored by means of a bolt 40 held in the end member 6 by passing through an opening provided therein for the purpose, being held secure by clamping the end member 6 between a collar or flange 42 and a nut 44.

A second set of contacts 46, 48, 50 and 52 is provided for engagement with the first set. It is readily seen from the drawings that each of the first set of contacts provides a concave cone which is engageable with the convex cone of the second set of contacts. Each of the second set of contacts consists of the aforesaid convex conical contact engaging member 54 held in place in an insulating contact holder 56 by any suitable means, as, for example, by means of a thread on a shaft 58 integral with the contact engaging member 54 which in turn engages a threaded flange bushing 62. Connecting conductor 64 electrically connects the contacts 46 and 52 by being clamped between one face of the member 56 and the underside of the conical engaging member 54 in each case. Similarly the connecting conductor 66 electrically connects the contacts 48 and 50.

The second set of contacts is reciprocable axially relative to the first set of contacts by means of the insulating contact carrier member 56 being mounted on an actuating rod 68. As is readily seen in Fig. 2, contact carrying member 56 is clamped between a shoulder 70 and a washer 72 by means of a nut 74. Actuating rod 68 is reciprocable in a bushing 76 in the end member 2. Rod 68 is secured against rotation by the indexing finger 78 held in place in one of the serrations of the serrated member 80. It will be seen that the serrated member 80 is preferably integral with the end member 2. Finger 78 is yieldably mounted on a spring 82 by means of suitable fastening members 84. Spring 82 is secured to a block 86 by means of a threaded member 88. Finger 78 is pivotally secured to block 86 by means of a pin 89. Block 86 may be held against rotation relative to rod 68 by a threaded member 90 which passes through the block and engages the surface of the rod at its outer end.

The serrated member 80 is provided with a plurality of notches 92, 94 and 96 to give the reciprocable contacts three indexed positions, as will be more fully explained below.

Actuating rod 68 is provided with a collar 98; one end of a spring 100 bears against the outer face of collar 98 and the other end of the spring bears against the bottom of a cylindrical boss 102 which may be and preferably is formed integral with the end member 2. The spring 100 thus biases the actuating rod 68 to the right, as seen in Fig. 2. Rod 68 and its associated contact carrying member 56 may be reciprocated axially to the left, as seen in Fig. 2, by manual means. Because of the strength of the spring 100, it is desirable to provide cam means with a substantial mechanical advantage. The cam means con-

sists of a helical cam surface 104 and a rotatable cam follower 106. The cam follower 106 is integral with a hub 108, which is rotatable on bushing 76 by means of an integral handle 110. A thrust bearing, indicated generally at 112, mounted in the hub 108, contacts the inner face of block 86 and serves to force the block 86 leftward to compress spring 100 when handle 110 is turned counterclockwise, as seen in Fig. 1.

The end member 2 is formed with a toroidal recess 114 in which is disposed a coil 116. Coil 116 will be connected in any suitable manner in the armature circuit, as will be readily understood by those skilled in the art.

A hinge member 118 having a slot 120 is secured to the side of the end member 2, more specifically to the shell 122 which forms the outer limits of the toroidal recess 114. Screws 124 pass through the slot 120 and engage the shell 122 to hold the hinge member 118 in position on the shell. The cooperation between the screws and the slot permits adjustment of the hinge member in a direction parallel to the axis of the coil 116.

A magnet armature 126 is hingedly mounted adjacent one end of coil 116 by means of a second hinge member 128, being secured by any suitable means, such as screws 130. Hinge member 128 cooperates with hinge member 118 to form a complete hinge.

A cam 132 is adjustably secured to shell 122 by screws 134 cooperating in a slot 136. A roller cam follower 138 is rotatably mounted on a pin 140 in a latch member 142; see Fig. 8. The latch member 142 is slotted, as shown at 144, and a screw 146 cooperates with the slot to make the latch member slidable along the armature 126 in a direction which lies in a plane which includes the axis of rod 68 and is therefore substantially parallel to the axis of movement of the second set of contacts as they reciprocate into and out of engagement with the first set of contacts. Two pins 148, one on each side of the latch member 142, serve as additional guide means to maintain the latch member 142 in proper alignment. The inner end of the latch member is provided with a semi-circular recess 150. As is best seen in Fig. 7, this recessed end of the latch member is adapted to be moved inward radially at one end of a reduced diameter portion 152 on rod 68 to cooperate with a shoulder 154.

A loop spring 156 bears against hinge member 128 and against the slidable latch 142 to bias the latter against the cam 132.

Operation

Reference is now had to the circuit diagram shown in Fig. 17 in which contacts 10 and 14 of the above described first set of contacts are connected in the armature circuit of a direct current shunt field motor M, and contacts 12 and 16 are connected to the two conduits L₁ and L₂ respectively of a direct current power source. The shunt field F is shown as being permanently connected to the power source by means of conductors C₁ and C₂. For motor rotation in one direction, the second set of contacts will be so oriented as to cause connecting strap 64 to close a circuit between contacts 10 and 12 and to cause connecting strap 66 to close a circuit between contacts 16 and 14. For rotation in the reverse direction, the second set of contacts will be so oriented as to close a circuit between contacts 10

and 16 and to close a circuit between contacts 12 and 14.

For a detailed discussion of the mechanical functioning of the switch, reference will first be had to the operating position shown in Fig. 7. With the switch parts in the position shown in that figure, the first set of contacts and the second set of contacts are in conducting engagement. Let it now be assumed that it is desired to reverse the motor. To accomplish that objective, the operator turns the motor controller to its off position. In many motor applications, the motor and the apparatus driven thereby will continue to coast rather than to stop rotating immediately. A long as motor M is turning over at any appreciable speed, there is a substantial counter-E. M. F. generated, and this E. M. F. is enough so that a damaging arc would be set up between the two sets of contacts if an attempt were made to disengage them preparatory to orienting them for reverse operation of the motor. The E. M. F. thus generated makes an electromagnet of the coil 116 which is sufficiently strong to hold the armature 126 attracted against the end of the coil in the position shown in Fig. 7, in which the cam follower 138 is shown rolled up to a high point on cam 132 in such a manner as to slide the latch member 142 radially inward against the bias of loop spring 156. In this position, the inner end of the latch member is located so as to cooperate with the shoulder 154 on the rod 68 to prevent disengagement of the second set of contacts from the first set of contacts, should such disengagement be attempted.

It will be understood from the foregoing that the cam follower 138, latch member 142 and the loop spring 156 constitute latch means to prevent disengagement of the second set of contacts from the first set.

It will be understood by those skilled in the art that the hinge member 118 and the cam 132 may be adjusted along the axis of the coil 116, in order to adjust the air gap in such a manner as to permit release of the latch means at a point where the counter-E. M. F. is not great enough to cause destructive arcing, should the two sets of contacts be disengaged. As will be understood by those skilled in the art, the loop spring 156, as well as the air gap, will determine what that E. M. F. amounts to.

Let it now be assumed that the armature has slowed down to such a point that the counter E. M. F. is below the danger point, whereupon the latch means will assume the position shown in Fig. 2. The second set of contacts can then be moved out of engagement with the first set of contacts by counterclockwise (as seen in Fig. 1) rotation of handle 110, causing cam follower 106 to ride along the helical surface of cam 104, causing retraction of the second set of contacts from the first set of contacts, after which the parts will occupy a position very much as shown in Fig. 6 (but note that the orientation of the second set of contacts in Fig. 6 is different from that shown in Figs. 7, 8, 9 and 10). With the rod 68 thus moved to the left as far as it can go, and spring 100 being thus compressed a maximum, indexing finger 78 may be moved out of the notch 96 it occupies in Fig. 9 and into notch 92. The handle 110 is thereupon moved clockwise to enable the spring 100 to reciprocate rod 68 to the right whereupon the second set of contacts engages the first set but in a new orientation, namely, the position shown in Figs. 11 and 12. The motor controller can then be turned

to the on position, and the motor will operate in a direction which is the reverse of its operation when the switch parts are in the position shown in Figs. 7, 8, 9 and 10.

It will be noted that the serrated member 80 is provided with an intermediate notch 94. When the indexing finger 78 lies in notch 94, and spring 100 is fully expanded, the second set of contacts lies substantially in the plane of the first set of contacts, but the individual contacts of the second set then are disposed between the individual contacts of the second set. This position is illustrated in Figs. 1, 2 and 4, especially Fig. 4.

It will be noted that the notches in the indexing member 80 are sufficiently deep, that the indexing finger cannot be moved out of a notch against the resistance of spring 82 to attempt a reorientation of the second set of contacts in relation to the first set, unless the contacts are first separated by movement of the handle 110 counterclockwise as seen in Fig. 1. Thus there are provided two interlocks against reversing of the switch until it is safe to do so. The first interlock is provided by the latch means consisting of the cam follower and latch 142 cooperating with the shoulder 154 on the reciprocable actuating rod 68. The second interlock consists of the indexing finger 78 lying in one of the deep notches of the serrated member 80.

It will be found that among the advantages of a switch made according to this invention is the feature of safety whereby the operator of the switch is safeguarded against dangerous arcing across the contacts because he will not be able to operate the switch as long as the motor armature is rotating at such a speed as could cause such arcing. Another advantage is the feature of orienting the contacts of the two sets in such a manner that the contacts of one set lie between the contacts of the other set, even though the position of the switch is such that the contacts of the two sets lie substantially all in the same plane. Other advantages will readily be apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In an electric switch device having at least one contact movable to open and close an electric circuit and lock means to prevent movement of the contact, the combination of actuating means reciprocable to move said contact into circuit opening and closing position, a shoulder carried by the actuating means, electrical means energizable to prevent said contact movement, means responsive to energization of said electrical means and mounted for movement upon energization thereof, a latch member carried by said responsive means and movable into engagement with said shoulder, a cam follower connected to move the latch member into said engagement upon movement of the responsive means, and a cam positioned to engage the cam follower and adapted to move the cam follower to effect the aforesaid movement of the latch member.

2. A switch device as in claim 1, in which the responsive means is a platelike member hingedly

mounted for pivotal movement, and the latch member is slidably carried by the platelike member.

3. A switch device as in claim 2, in which the cam follower is carried by the latch member adjacent an edge of said platelike member, said hinged mounting of the platelike member being at an edge thereof opposite the latch member.

4. A switch device as in claim 3, in which a spring is mounted on said platelike member and engages the latch member to oppose movement thereof by the cam follower.

5. A switch device as in claim 4, in which said contact is carried by the actuating means for reciprocation therewith into circuit opening and closing position; and in which the cam follower is a roller carried by the latch member.

6. A switch device as in claim 1, in which said contact is carried by the actuating means for reciprocation therewith into circuit opening and closing position; and in which the cam follower is a roller carried by the latch member.

7. In an electric switch device having at least one contact movable to open and close an electric circuit and lock means to prevent movement of the contact, the combination of an actuating rod reciprocable to move said contact into circuit opening and closing position, a shoulder on the rod, an electromagnet energizable to prevent said contact movement, an armature adjacent one pole of the electromagnet and mounted for movement toward and away from said pole upon energization and deenergization of the magnet, a latch member carried by the armature and movable into engagement with the shoulder on the rod, a cam follower connected to move the latch member into said engagement upon movement of the armature toward said pole, and a cam positioned

20 to engage the cam follower and adapted to move the cam follower to effect the aforesaid movement of the latch member.

5 8. A switch device as in claim 7, in which the armature is a platelike member hingedly mounted for pivotal movement and having an opening for the actuating rod, and the latch member is slidably carried by the platelike member.

10 9. A switch device as in claim 8, in which the cam follower is a roller carried by the latch member, and in which said contact is carried by said rod for reciprocation therewith into circuit opening and closing position.

15 10. A switch device as in claim 7, in which the cam follower is a roller carried by the latch member, and in which said contact is carried by said rod for reciprocation therewith into circuit opening and closing position.
